A. H. SHIPLEY

BRUSH MAKING MACHINE

Filed Sept. 10, 1920

Patented June 12, 1923.

1,458,783

UNITED STATES PATENT OFFICE.

ARTHUR HAMMOND SHIPLEY, OF LEICESTER, ENGLAND.

BRUSH-MAKING MACHINE.

Application filed September 10, 1920. Serial No. 409,472.

(GRANTED UNDER THE PROVISIONS OF THE ACT OF MARCH 3, 1921, 41 STAT. L. 1313.)

To all whom it may concern:

Be it known that I, ARTHUR HAMMOND SHIPLEY, subject of the King of Great Britain, residing at Leicester, in the county of Leicester, England, have invented certain new and useful Improvements in or Relating to Brush-Making Machines (for which I have filed application in England May 21, 1917, Patent No. 115,887), of which 10 the following is a specification, reference being had therein to the accompanying drawing.

This invention relates to brush-making machines and concerns more especially, 15 though not exclusively, machines for filling brush heads, backs or stocks.

In certain kinds of machines for inserting tufts or bunches of bristles or the like into the holes previously drilled in the stock or 20 head of a brush, an arrangement of mechanism is employed for holding the brush head or stock up to the inserting tool or member, said mechanism including as one of its features a rest or support which comes into position behind the stock when the latter is placed against the tool and held by the operator. This rest is so arranged as to be capable of adjustment by a hand device relatively to the inserting tool or member for 25 the purpose of adapting the machine to deal with brush heads or stocks of different thicknesses, and it also has combined with it automatically acting locking means which come into operation to prevent retirement 30 of the rest after it has been moved towards the inserting tool by certain mechanical devices provided for the purpose. The said locking means serve to hold the rest in the operative position to support the stock during 35 the inserting operation and they are so arranged as to automatically lock the rest in whatever position it may have been moved to. The adjustment above referred to must be made prior to the rest being 40 moved to and locked in the operative position and it frequently happens that it is desirable to effect further adjustment of the rest after it has reached the said operative 45 position, but as this cannot be effected the 50 complete cycle of the machine's operation must be accomplished to enable the locking means to release the rest. It also sometimes happens that it is desirable to release the

rest after it has been automatically locked as for instance when the stock is not correctly positioned. 55

The present invention therefore has for its object the provision of means in a machine of the kind mentioned whereby the release of the rest or holding mechanism may be effected by and at the will of the operator at any time after said rest has become automatically locked and before it is automatically unlocked. The said means constituting this invention may be of such a character 60 that, if desired, they may be used to put the automatic locking means out of action entirely. 65

In a brush filling machine of known construction, the brush head, back or stock is supported, while held by the operator, against the thrust of the filling or inserting tool, by a rest which is slidable relatively towards and from said tool and has combined with it a toothed rack. Arranged to engage the rack are a number of spring actuated pawls controlled by a lever or similar member which in turn is operated by a part of the rest actuating mechanism, in such a manner that it allows the pawls to engage the rack at the right time to lock the rest and also disengages the pawls from the rack when the rest is to be retracted on the completion of the filling operation, i. e. after each bunch or tuft has been inserted into 85 a hole. 70

The object of this invention is achieved in such machine by providing in association with the pawl controlling lever or member a device operable by hand or foot to move said lever or member and cause it to effect disengagement of the pawls from the rack. 80

Conveniently the controlling lever or similar member has combined with it a cam-lever operable by hand and arranged so that when turned in one direction it raises the controlling lever and thereby disengages the pawls from the rack, and when turned in the opposite direction it releases said controlling lever so that the latter is able to operate for its intended purpose. 95

To enable the invention to be clearly understood a practical embodiment of the same is shown by way of example in the accompanying drawing applied to a brush-fill- 100 105

ing machine having an arrangement of mechanism of the kind hereinbefore referred to for supporting the stock.

In the drawing:—

5 Figure 1 is a side elevation of the part of the machine concerned by the present invention.

10 Figure 2 is a sectional elevation of the controlling lever of the machine equipped 75 with operating means according to the present invention.

15 Figure 3 is a plan of the said controlling lever.

20 Figure 1 is drawn to a smaller scale than 15 Figures 2 and 3 and in the several figures like parts are designated by the same reference characters.

25 In the portion of the brush-filling machine shown in Figure 1 of the drawing, 1 is the guiding nozzle surrounding the inserting tool, 2 is the rest which comes into position behind the brush stock 3 when the latter is placed in position against the nozzle. The rest 2 is slidable longitudinally 30 through bearings 4 and is fitted with an adjusting screw 5 by which it is connected to a spring part 6 of an actuating lever 7. The lever oscillates upon a pin 8, being moved by the combined action of an eccentric of 35 cam 9 and a spring 10. The spring part 6 of the lever 7 yieldingly moves the rest to and fro and the rest may be adjusted relatively to the nozzle 1 so that its operative position may be varied as required to suit 40 brush stocks of different thicknesses.

45 The sliding rest 2 is provided thereon at its rear end with rack teeth 11 (Figure 2) with which a series of pawls 12 (Figures 1 and 2) engage to lock the rest against retiring movement. The pawls are pivotally mounted at 13 on a supporting lever 14 (Figure 1) resiliently controlled by the rod 15 and spring 16 the pawls being pressed into engagement with the rack teeth by 50 springs 17.

55 When by movement of the lever 7 in the direction indicated by the arrow, the rest 2 is moved and comes into contact with the back of the stock 3 (the said stock being held in engagement with the nozzle by the operator), the spring part 6 of the lever becomes more or less bowed according to the degree of pressure determined by the prior adjustment or setting of the rest in relation to the work, and upon the rest reaching its position the pawls 12 engage the rack teeth 11 and automatically lock the rest in whatever position it is moved to, said locking preventing retiring movement but 60 not forward movement of the rest. Upon completion of the inserting operation the lever 7 is moved by the aforesaid means in the opposite direction to that previously described and during this movement an extension or finger 18 on the lever slides under a

lever-cam 19 and upon passing from the lip 20 of same to the cam part 21 raises this lever-cam on its pivot 22 which movement by means of a screw 23 raises the controlling lever 24. This latter lever is pivotally mounted at 25 and its screw 23 rests upon a lug 26 on the side of the lever-cam 19. The free end 27 of the controlling lever 24 is situated underneath lips 28 projecting from the pawls 12 (Figures 1 and 2) so that when it is raised as aforesaid by the lever-cam 19 it will lift the pawls from engagement with the rack teeth 11 as represented by the dotted lines in Figure 2. The pawls 12 having been disengaged from the rack teeth the rest 2 is free to be moved rearwards by the continued action of the lever 7 thus releasing the work and allowing the operator to change its position and bring another hole into engagement with the nozzle preparatory to inserting the next bunch of bristles. 85

90 During the next advance movement of the rest 2 to engage with the newly positioned stock, the extension or finger 18 of the lever 7 moves forward under the cam part 21 of the lever-cam 19 and thus holds the pawls raised until upon or just prior to the rest reaching the operative position, when said finger passes from the cam part 21 to the lip 20, and in doing so, allows the lever-cam 95 19 to fall, this in turn allowing the controlling lever 24 to fall so that the pawls 12 are pressed down by their springs 17 to engage the rack teeth 11 and lock the rest.

100 Thus it will be seen that the engagement of the pawls 12 with the rack teeth and also their disengagement from said teeth to respectively lock and unlock the rest is effected automatically by means of the extension or finger 18. 105

110 Now from the foregoing description it will be seen that after the rest has been advanced to and become locked in its operative position, no adjustment of this member in a rearward direction can be effected by the device 5, neither can the stock be removed. To perform either of these operations the rest must be unlocked and with the arrangement described it is usually necessary to allow the machine to complete its cycle so that the finger 18 effects the unlocking to free the part 2. In other words, there is no provision in the arrangement referred to for unlocking the rest at will when it occupies its operative position. 115

120 As previously stated herein, it is sometimes desirable to further adjust the rest 2 relatively to the nozzle 1 after the rest has assumed the operative position, and further it is sometimes desirable to release the rest for the purpose of enabling the stock to be altered in position. For instance, if the operator in moving the stock misses a hole or otherwise gets the stock wrongly positioned as the rest comes up to its work, it 125 130

is distinctly advantageous to be able to release the rest so that the machine can complete its cycle without causing damage to itself or the work.

5 In the form of mechanism described, this is made possible according to the present invention by combining with the controlling lever 24 a cam-lever 29 (Figures 1, 2 and 3) situated in a slot 30 and mounted upon a pin 31 in said lever 24. When this cam-lever occupies the position shown in full lines, the controlling lever 24 is free to be influenced by the finger 18 in the manner already described for automatically locking 10 and unlocking the rest 2. When however the said cam-lever is turned by hand to the position indicated by dotted lines in Figure 2 the lower cam portion or end 32 rides upon a fixed part 33 and thereby effects the 15 raising of the lever 24 on its pivot 25 as also shown by dotted lines, this rising of said lever lifting the pawls clear of the teeth 11 as previously mentioned. A reverse movement of the cam-lever 29 (from 20 dotted to full line position, Figure 2) allows the controlling lever to fall and lower the pawls into action. Thus at will by moving, the cam-lever 29 the operator can, such for example as for the purposes previously 25 mentioned, release and lock the rest 2 while the latter occupies its operative position.

In the form shown in Figure 2, the cam-lever device 29 is arranged to move to positions upon opposite sides of the vertical or 30 dead centre, and is restricted by contact with the end 34 of the slot thus being retained in the respective positions without the assistance of any subsidiary means the downward pressure of the lever 24 imparted by 35 gravity and the springs 17 acting thereon

by the lips 28, tending to prevent accidental movement of the device from either position.

What I claim then is:—

1. In a brush-making machine, in combination, a slidable rest, means to automatically lock said rest in the operative position, a lever to control said locking means, mechanical means to operate said lever to effect locking and unlocking said rest, and a manually operable cam-lever pivotally 45 mounted in the controlling lever adapted upon being turned in one direction to move the controlling lever so that it renders the locking means inoperative and, upon being turned in the opposite direction, to move 50 said lever so that it makes said locking means operative.

2. In a brush-making machine, in combination, a slidable rest, means to automatically lock said rest in an operative position a lever to control said locking means, mechanical means to operate said lever to effect locking and unlocking of the rest, and a manually operable cam-lever pivotally 60 mounted in the controlling lever and situated within a slot therein, so as to be movable in one direction to raise said controlling lever and in the other direction to lower same for the purpose of respectively unlocking and locking the rest, said cam lever being moved to respective positions on opposite sides of the dead centre and being limited in movement by the ends of the slot 65 in which it is situated.

In testimony whereof I affix my signature in presence of two witnesses.

ARTHUR HAMMOND SHIPLEY.
